(57) **CLAIM**

The ornamental design for toothbrush head cover, as shown and described.

DESCRIPTION

FIG. 1 is a front perspective view of toothbrush head cover, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and

FIG. 8 is a bottom view thereof; and,

FIG. 9 is a perspective view of the open state of FIG. 1. The broken lines in the drawings illustrate the portions of the toothbrush head cover, which form no part of the claimed design.

1 Claim, 9 Drawing Sheets(56)
